UNITED STATES PATENT OFFICE.

ROSWELL A. MOORE, OF WATERBURY, CONNECTICUT, ASSIGNOR TO WATERBURY BUCKLE CO., OF WATERBURY, CONNECTICUT, A CORPORATION.

SLIDE BUCKLE.

Application filed November 5, 1923. Serial No. 672,734.

To all whom it may concern:

Be it known that I, ROSWELL A. MOORE, a citizen of the United States, residing at Waterbury, in the county of New Haven and State of Connecticut, have invented a new and useful Improvement in Slide Buckles; and I do hereby declare the following, when taken in connection with the accompanying drawings and the characters of reference marked thereon, to be a full, clear, and exact description of the same, and which said drawings constitute part of this application, and represent, in—

Fig. 1 a view in front elevation of a slide-buckle constructed in accordance with my invention.

Fig. 2 an edge view thereof.

Fig. 3 a view looking toward the lower edge thereof.

Fig. 4 a sectional view on the line 4—4 of Fig. 1.

Fig. 5 a detached plan view of the buckle-frame.

Fig. 6 a plan view of the slide with its mounting-finger shown prior to being bent to embrace the side-bars of the buckle-frame.

My invention relates to an improved slide-buckle designed with particular reference to be used on the non-elastic straps of abdominal supporters, though not so limited, the object being to provide a simple, strong, convenient and highly efficient buckle of the character described in which the straps are held by the combined action of deflection and friction, rather than by prongs piercing them.

With these ends in view, my invention consists in a slide-buckle having certain details of construction as will be hereinafter described and pointed out in the claim.

In carrying out my invention, as herein shown, I employ a substantially rectangular, sheet-metal buckle-frame having a webbing-opening 10, a lower gripping-bar 11, parallel side-bars 12, and along its upper side an offset containing a long narrow slot 13 designed for the reception of the short strap (not shown) by means of which the buckle is fastened to the garment. The upper or gripping-edge of the lower bar 11 is con-

toured to form three uniform scallops 14, separated by two upstanding, web-holding points 15, but the number of these scallops and points may be varied as desired, so long as they exist in plurality. The stamped or embossed, sheet-metal slide 16 is narrower than the width of the webbing-opening 10 and formed at its ends with complementary mounting-fingers 17, which are bent in somewhat angular form, so as to loosely embrace the respective side-bars 12 of the buckle-frame, upon which the slide is free to move up and down. The main body of the slide is struck forwardly to form a wide, longitudinal rib 18, the lower edge of which is embossed or indented to form three scallops 19 conforming in curvature to the scallops 14 of the buckle-frame and with two indentations 20 registering with the web-holding points 15 thereof, while the lower edge of the slide is formed with a scalloped skirt 21 having three scallops 22 separated by notches 23. When the slide is moved downward, the scallops of its embossed front fit the scalloped upper edge of the lower bar of the buckle-frame, while, at the same time, the scalloped skirt of the slide extends downward back of the same.

Under the construction described, the scalloped upper edge of the lower bar of the frame, the embossed scallops and the scalloped skirt of the slide all co-act to deflect and bite into the webbing, so as to firmly grip the same without any actual penetration of the fabric thereof. The slide, moreover, is so loose upon the frame that it is very conveniently moved into and out of its gripping position, and for the same reason, accommodates non-elastic webbing of some range in thickness.

I claim:

As a new article of manufacture, a slide-buckle having a substantially rectangular, flat, sheet-metal buckle-frame formed with a webbing-opening, with side-bars and with a lower bar, the upper edge of which is formed with a plurality of scallops and points, and a slide formed at its ends with mounting-fingers loosely embracing the side-bars of the frame, and forwardly struck

2
up to form a longitudinal rib, the lower edge of which is embossed to conform to the scallops of the lower bar of the frame, and also formed with a depending skirt scalloped 5 to conform to the scalloping of the said bar, and also to the scalloping of the lower edge of the struck-up rib of the slide.

In testimony whereof, I have signed this specification in the presence of two subscribing witnesses.

ROSWELL A. MOORE.
